[57] CLAIM

The ornamental design for a cellular telephone with extendible microphone, as shown and described.

DESCRIPTION

FIG. 1 is a front right side view of a cellular telephone with an extendible microphone according to our new design in its opened position; and,

FIG. 2 is a rear left side view of a cellular telephone with an extendible microphone according to our new design in its opened position.

The portions of the claimed article not shown or apparent in the drawings are not considered to be a part of the claimed design.
